[57] CLAIM

The ornamental design for a travel steam iron, as shown and described.

DESCRIPTION

FIG. 1 illustrates a top, front and left side perspective view of my new design for a travel steam iron in the operating position;

FIG. 2 illustrates a top view thereof;

FIG. 3 illustrates a left side elevational view thereof;

FIG. 4 illustrates a right side elevational view thereof;

FIG. 5 illustrates a front elevational view thereof;

FIG. 6 illustrates a rear elevational view thereof;

FIG. 7 illustrates a bottom view thereof;

FIG. 8 illustrates a top, front and left side perspective view of my new design for a travel steam iron in the collapsed position;

FIG. 9 illustrates a top view of the iron of FIG. 8;

FIG. 10 illustrates a left side elevational view of the iron of FIG. 8;

FIG. 11 illustrates a right side elevational view of the iron of FIG. 8;

FIG. 12 illustrates a front elevational view of the iron of FIG. 8;

FIG. 13 illustrates a rear elevational view of the iron of FIG. 8; and,

FIG. 14 illustrates a bottom view of the iron of FIG. 8.
